UNITED STATES PATENT OFFICE.

JOHN M. FACKLER, OF NEW HOLLAND, PENNSYLVANIA, ASSIGNOR TO NEW HOLLAND MACHINE COMPANY, OF NEW HOLLAND, PENNSYLVANIA, A CORPORATION OF PENNSYLVANIA.

HUMIDIFIER PAN.

Application filed October 1, 1926. Serial No. 138,942.

This invention relates to humidifying pans for hot-air furnaces and has for its object the provision of a water pan or container of inexpensive construction which may be easily placed in position in the furnace and will be firmly held without the use of bolts or similar fastening devices. Another object of the invention is to provide a pan which will furnish an ample supply of moist vapor to circulate through the building with the hot air and counteract the effects of dry heat upon the woodwork of the building, the furniture therein, and the health of the occupants. The invention is illustrated in the accompanying drawing and will be hereinafter fully described, the novel features being particularly pointed out in the appended claims.

In the drawing,

20 Figure 1 is a vertical section of a portion of a hot-air furnace showing the improved pan in position therein;

25 Figure 2 is a top plan view of the pan with the adjacent parts of the furnace in horizontal section.

In the drawing, 1 designates a part of the outer shell or casing of a hot-air furnace, 2 a part of the fire-box, 3 a part of the grate-ring, and 4 the ash pit.

30 In carrying out the present invention, an opening 5 is formed through the shell 1 and a frame plate 6 is secured over the end portions of said opening, the opening and frame being located immediately over the front 7 of the ash pit. The front top plate 8 of the ash pit extends from the grate ring 3 to the frame plate 6 and is provided with an up-standing boss 9 having a central opening therethrough, the top of the boss being in a 35 horizontal plane somewhat above the horizontal plane of the lower side of the opening through the frame plate 6. The water pan 10 is a single integral casting having an up-standing rim defining straight parallel sides and arcuate back and front portions, the pan being rather shallow and fitting closely but slidably through the frame plate 6 so as to be partly supported thereby. The front 45 curvature of the pan harmonizes with the shell of the furnace while the curvature of the back of the pan permits it to assume a concentric relation to the fire place and obtain maximum exposure to the heat radiating therefrom. Near the back of the pan, a 50 teat or nipple 11 rises from the bottom there-

of and the base of this teat or nipple is concave or socketed to fit over and rest firmly upon the boss 9 whereby to aid in supporting the pan and preventing its displacement. To increase the stability of the pan on its support, the lower end of the nipple is slightly extended to define a lug 12 fitting closely within the opening in the top of the boss 9, and the nipple has an attenuated bore or passage 13 extending vertically therethrough for a purpose which will presently appear.

The pan may be filled by manually pouring water through the part thereof projecting beyond the frame plate 6. It is obviously desirable, however, to provide for an automatic replenishment or supply of the water and, in actual practice, a pipe 14, connected with any convenient source of supply, will be provided to lead the water to the 75 pan, a regulating valve 15 being interposed in the pipe and adjusted to permit the flow of water at the desired rate. The outlet 16 of the regulating valve is arranged directly over an opening 17 in a plate or cover 18 80 which rests on the front end portion of the pan and extends over the same to prevent objects dropping into the pan.

The pan is fitted in place by being inserted through the opening in the frame plate 6 85 and pushed in until it rides over and seats upon the boss 9. The water is then turned on through the supply pipe until the pan is filled to the desired level, and the regulating valve is adjusted to maintain that level by 90 restricting the inflow to a rate about equal to the rate of evaporation. Should the inflow exceed the rate of evaporation, there will be an overflow through the passage 13 to the ash pit whereby excess volume of 95 water will be accommodated and the ashes will be moistened, the rising of dust from the ash pit through the furnace and the settling of such dust upon objects in the furnace room being thereby avoided. It will 100 be noted, upon reference to Fig. 1 that the top wall of the ash pit is inclined upwardly and outwardly and that the back wall of the pan is spaced from the fire box so that the heat radiating from the fire box and the 105 grate ring may circulate under the pan and evaporation will be effectually accomplished. Inasmuch as the pan is located at the air space between the inner furnace shell and the outer casing, the vapor rising from the 110

pan will mingle at once with the hot air flowing through the circulating flues. The pan may be tilted in the plate 6 sufficiently to clear the boss 9 whereupon it may be

5 drawn forward from the furnace, when necessary, but it is to be noted that while only slight tilting is needed accidental tilting is practically impossible and the lug 12 prevents displacement unless the pan is tilted.

10 Having fully described my invention what I claim as new and desire to secure by Letters-Patent, is:—

1. In a hot-air furnace, the combination of an ash-pit having a boss on the upper

15 side of its top wall, and a water pan supported at its front portion by the casing of the furnace and a socket in its bottom to en-

gage over and rest upon the boss on the ash pit, the pan being further provided with an overflow outlet through the socket and the 20 boss.

2. In a hot-air furnace, the combination of an ashpit, a boss on the top wall of the ash pit having a central opening therethrough, a water pan having its front end portion 25 supported at the front end of the top wall of the ash pit, a socket in the bottom of the pan to engage over the boss, and a nipple within the pan having its lower end extended into the socket and engaging in the open- 30 ing in the boss.

In testimony whereof, I have signed this specification.

JOHN M. FACKLER.
